UNITED STATES PATENT OFFICE.

RUSSELL M. KNEISLEY, OF CARROLLTON, MISSOURI.

CLOTHES-LINE REEL AND TIGHTENER.

No. 926,576.

Specification of Letters Patent.

Patented June 29, 1909.

Application filed May 6, 1908. Serial No. 431,239.

To all whom it may concern:

Be it known that I, RUSSELL M. KNEISLEY, a citizen of the United States, residing at Carrollton, in the county of Carroll and 5 State of Missouri, have invented new and useful Improvements in Clothes-Line Reels and Tighteners, of which the following is a specification.

This invention relates to clothes line reels 10 and tighteners and has for its object to provide a simple and practical reel for the manipulation of clothes line, said reel embodying a plurality of drums in connection with means for winding and holding said drums 15 independently of each other, one of the drums being adapted for the reception of the clothes line and another drum being adapted for the reception of a hoisting line, whereby the line of the clothes may be tightened and 20 also raised and lowered.

With the above and other objects in view, the invention consists in the novel construction, combination and arrangement of parts as herein fully described, illustrated and 25 claimed.

In the accompanying drawings: Figure 1 is a side elevation of the clothes line reel and tightener applied to a support, showing also a clothes line and hoisting line connected 30 therewith. Fig. 2 is a front elevation of the reel. Fig. 3 is a vertical sectional view of the reel. Fig. 4 is a horizontal section through the reel taken in line with the shaft thereof.

The reel comprises a pair of oppositely arranged bracket arms 1, each of which is substantially U-shaped as shown in Fig. 3, the 35 said arms being connected together rigidly by top and bottom cross bars 2 and 3 respectively, which cross bars are provided with 40 apertures 4 and 5 for the reception of suitable fasteners such as screws whereby the reel as a whole may be secured to a suitable support 5' which may consist of a post, wall or fence and the like. The top and bottom 45 cross bars are provided with terminal angular flanges 6 and 7 adapted to receive fasteners 8 by which the cross bars are connected to the top and bottom portions of the bracket 50 arms 1. The projecting portions of the bracket arms 1 are also connected by an addi-

tional brace or cross bar 9 provided with terminal flanges 10 secured by fasteners 11 to said bracket arms. Journaled in the opposite bracket arms 1 is a reel shaft embodying 55 a pair of sections 12 and 13 and by reference to Fig. 4 it will be noted that one of the sections is provided with a pintle 14 which is received and works within a corresponding recess 15 in the other shaft section. In this way, the shaft sections are connected by an 60 interfitting engagement which admits of the relative and independent rotation of the shaft sections by means of operating cranks 16 and 17 which are mounted fast on the outer extremities of the shaft sections as indicated in Fig. 2. In the preferred embodiment of the invention, the shaft sections are 65 squared as shown in Figs. 3 and 4, and mounted upon each of said sections is a drum, one of said drums 18 being designed to receive 70 the clothes line illustrated at 19 while the other drum 20 is adapted to receive the hoisting line 21. On each shaft section there is also mounted a ratchet wheel 22 which is engaged by a corresponding pawl 23 to prevent 75 the drum from turning backward and unwinding the line after the line is wound thereon by means of the crank 16 or 17 as the case may be.

At a suitable distance above the reel there 80 is arranged a guide 24 which is shown for convenience in the form of a ring secured to the support 5 by means of a staple 25. The hoisting line is provided terminally with a guide block 26 through which the clothes 85 line 19 passes.

It will now be understood that after placing the clothes upon the line 19, said line may be wound up to any desired tension by turning the appropriate drum. The other 90 drum is then turned to wind up the hoisting line 21 which has the effect of elevating the pulley line 26 and raising the end portion of the clothes line in a manner illustrated in Fig. 1. The clothes line may be easily lowered 95 by unwinding the line 21 to the desired extent.

I claim:

A clothes line reel comprising a bracket, a divided shaft journaled in said bracket and 100

embodying sections having an interfitting engagement at their adjoining ends and adapted for relative rotation, drums fast on said shaft sections, one adapted to receive and wind a clothes line and another adapted to receive and wind a hoisting line, pawl and ratchet means to hold said drums from rotation in one direction, and operat-

ing cranks on said shaft sections whereby they are independently operable.

In testimony whereof I affix my signature in presence of two witnesses.

RUSSELL M. KNEISLEY.
